JOHN HENRY MORGAN, OF ALAMEDA, CALIFORNIA, ASSIGNOR OF ONE-HALF TO
WILLIAM I. FINCH, OF BERKELEY, CALIFORNIA.

FOLDING EGG-CONTAINER.

1,115,449.

Specification of Letters Patent. Patented Oct. 27, 1914.

Application filed August 8, 1913. Serial No. 783,712.

To all whom it may concern:

Be it known that I, JOHN H. MORGAN, a citizen of the United States, residing at Alameda, in the county of Alameda and State of California, have invented a new and useful Folding Egg-Container, of which the following is a specification.

My invention relates to improvements in containers especially adapted for shipping and handling eggs generally, to provide for holding the eggs separated and suspended on a resilient support so as to withstand shocks from careless handling; to provide a container that will be of light weight and yet strong and one that will unfold flat when not in use.

Further objects of my improvement are to provide an egg container that can be used repeatedly if desired, but constructed of inexpensive material so that it can be thrown away after the first shipment without material loss.

I attain these objects by the construction shown in the accompanying drawing, in which:-

Figure 1 is a longitudinal section of my improved container; Fig. 2 is a cross section of same on line A—B of Fig. 1; Fig. 3 is a plan of the lower section; Fig. 4 is a perspective view of the container; Fig. 5 shows the cut and scored blank which forms the container when folded; Fig. 6 is a side elevation, and Fig. 7 is an end view of the blank in its folded shape.

In Fig. 1, which is a vertical longitudinal section on the line C—D of Fig. 2, 1 represents the lower section and 2 the upper section, 4, 4, 4, represent tongues formed by cutting on the dotted lines 5—5 (Fig. 3) and scoring on the lines 6, 6, 6, and bending to form a nest or pocket for the egg, which is shown by dotted lines 7—7. The main body part of the lower section of the container is made of one piece of material, preferably cardboard, with one free edge at a, is scored and bent at b, c, d, e, and f, with the opposite edge at g, thus forming the inclined walls 9 and 10, the top 11, the side 12, the bottom 13, and the side 14. These walls are held in folded relation by a suitable fastener at 15, as shown in detail in Fig. 2. The side 14 extends above the top as shown at 16. Attached to the sides 12 and 14 are strips 17, by any suitable means, as the wire staples 18.

The upper container section is a duplicate of 55 the lower section, and the strips 17, bridge the joint between them when assembled.

The use of this container as shown in Fig. 2 is as follows:—Eggs are placed on end in the pockets of the lower section and the upper section is placed with its pockets over the upper ends of the eggs and pressed down until the upper section rests on the edges of the projecting side 16, and the projecting side 19 of the upper section rests on the lower 65 section, thus leaving a space between the contiguous sides of the two sections. In this position, the two sections are fastened together in any suitable manner, as with cord or adhesive tape. The eggs are supported 70 in the pockets by the resilience of the tongues 4, which is sufficient to carry the eggs with ordinary handling, but if the container should receive a shock severe enough to cause the eggs to go through the pockets, the 75 eggs will come in contact with the V-shaped walls, which on account of the shape, are resilient at the point where the eggs come in contact, and thus the eggs are doubly safeguarded against breakage.

Fig. 5 shows the form of the upper section in the flat, cut out and scored by the die to fold on lines b, c, d, e, f, as described, and for the ends 19 and the wings 20, scored to fold on the lines h, i, j, k, l, and m.

Fig. 4 is a perspective view showing the container tied with cord; also showing the reinforcing strip 17 extended across the ends and sides and covering the joint between the two sections.

From the construction described, it will be noted that I have provided resilient walled pockets for the eggs in the tongues 4, and rigid protective walls between said tongues and the outer walls of the sections, in the 95 inclined walls 9, 10. The edges of the extensions 16, 19, of the side walls of the rectangular chambers abut against the inside walls and thus form spacing members which tend to resist the relative crushing of the two sections. The overlapping strips 17, not only serve to connect together the two sections but to reinforce the side walls of the container at a zone that otherwise would be weak.

I am aware that containers have been patented with triangular chambers therein, and others show resilient egg-receiving pockets,

but so far as I am aware I am the first to combine these features in a unitary egg container.

Having thus described my invention what I claim as new, is:—

1. An egg-box consisting of two complementary sections, each section composed of a single sheet of suitable material, cut, scored and bent to form a rectangular chamber extending the entire length of the box and a triangular chamber within the walls of the rectangular chamber, the inside wall of the rectangular chamber forming the base of the triangular chamber and having egg-receiving pockets formed therein, the inside wall of one section being spaced from the inside wall of the opposed section, and said sheets being also cut, scored and bent to form end closing members.
2. An egg-box consisting of two complementary sections, each section composed of a single sheet of suitable material, cut, scored and bent to form a rectangular chamber extending the entire length of the box, and a triangular chamber within the walls of the rectangular chamber, the inside wall of the

rectangular chamber forming the base of the triangular chamber and having egg-receiving resilient walled pockets formed therein, and one of the side walls of each section extending beyond the inside wall of its section to form a spacing member between said sections, said sheets also cut, scored and bent to form end-closing members.

3. An egg-box consisting of two complementary sections, each section composed of a single sheet of suitable material cut, scored and bent to form a rectangular chamber extending the entire length of the box and a triangular chamber within the walls of the rectangular chamber, the inside wall of the rectangular chamber forming the base of the triangular chamber and having egg-receiving pockets therein, the inside walls of said sections being spaced apart, and means for closing the joint between said sections and reinforcing the walls at said joints.

JOHN HENRY MORGAN.
